Primary Examiner — Mojtaba Tehrani*(74) Attorney, Agent, or Firm* — Nitin Kaushik(57) **CLAIM**

The ornamental design for a bubble wand, as shown and described.

DESCRIPTION

FIG. 1 is a front perspective view of a bubble wand, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The evenly broken lines disclose unclaimed portions of the bubble wand; the dash-dot-dash broken lines disclose boundaries of the isolated and partial views; the broken lines in the drawings form no part of the claimed design.
